(57) **CLAIM**

The ornamental design for a drinking straw, as shown and described.

DESCRIPTION

FIG. 1 is a perspective view of a new design for a drinking straw.

FIG. 2 is a top view of the drinking straw of FIG. 1.

FIG. 3 is a bottom view of the drinking straw of FIG. 1.

FIG. 4 is a left side view of the drinking straw of FIG. 1.

FIG. 5 is a right side view of the drinking straw of FIG. 1.

FIG. 6 is a front view of the drinking straw of FIG. 1.

FIG. 7 is a back view of the drinking straw of FIG. 1.

FIG. 8 is a perspective view of another configuration of a new design for a drinking straw.

FIG. 9 is a top view of the drinking straw of FIG. 8.

FIG. 10 is a bottom view of the drinking straw of FIG. 8.

FIG. 11 is a left side view of the drinking straw of FIG. 8.

FIG. 12 is a right side view of the drinking straw of FIG. 8.

FIG. 13 is a front view of the drinking straw of FIG. 8; and,

FIG. 14 is a back view of the drinking straw of FIG. 8.

Broken lines in the drawings depict features that form no

part of the claimed design.

1 Claim, 6 Drawing Sheets
